(57) **CLAIM**

The ornamental design for a flexible printed wiring board with device, as shown and described.

DESCRIPTION

FIG. 1 is a front view of a flexible printed wiring board with device showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is an enlarged top plan view of a section taken along line 7-7 in FIG. 3;

FIG. 8 is a bottom plan view of FIG. 7;

FIG. 9 is a front view of FIG. 7;

FIG. 10 is a rear view of FIG. 7;

FIG. 11 is a right side view of FIG. 7;

FIG. 12 is a left side view of FIG. 7;

FIG. 13 is a perspective view of FIG. 7; and,

FIG. 14 is another perspective view of FIG. 7 shown in a used condition with a Photovoltaic module, junction box and Fresnel lens shown in broken lines.

The even dashed broken lines shown in the drawings represent portions of the flexible printed wiring board with
